UNITED STATES PATENT OFFICE.

KINDERMAN M. BOBLETT, OF TOLEDO, OHIO.

RADIATOR.

1,140,494.

Specification of Letters Patent. Patented May 25, 1915.

Application filed April 1, 1912. Serial No. 687,619.

To all whom it may concern:

Be it known that I, KINDERMAN M. BOBLETT, a citizen of the United States, residing at Toledo, in the county of Lucas and State 5 of Ohio, have invented certain new and useful Improvements in Radiators, of which the following is a specification.

My invention relates to fluid cooling apparatus, or condensers, and particularly to radiators for use in connection with explosive engines, and is especially adapted for 10 automobile use.

The invention, however, is not limited to such use, but may be employed as a condenser in connection with steam engines, or in connection with refrigerating apparatus, or it may be employed as a radiator for 15 heating purposes.

The object of the invention is to simplify 20 the structure as well as the means and mode of operation of such devices, whereby they will not only be cheapened in construction, but will be more efficient and economical in operation, and unlikely to get out of 25 pair.

A further object is to provide an improved form of radiator which will present to the atmosphere a maximum amount of radiating surface, which will be stanch and 30 compact, and which will comprise a plurality of identical units which are assembled to form radiators of different sizes or proportions.

With the above primary and other incidental objects in view as will more fully appear in the specification the invention consists of the features of construction, the parts and combinations thereof, and the mode of operation or their equivalents, as 35 40 hereinafter described and set forth in the claims.

Referring to the drawings, Figure 1 is a front elevation of the assembled radiator. Fig. 2 is a detail perspective view of one of 45 the radiator units somewhat expanded to better show the configuration of the strip of material from which the unit is constructed. Fig. 3 is a detail transverse sectional view. Fig. 4 is a detail perspective view of several 50 radiator units adjusted side by side illustrating the intermediate water passages or conduits between succeeding units. Fig. 5 is a detail sectional view disclosing the water passages or conduits. Figs. 6, 7, 8

and 9 are perspective views of modifications 55 of the constructions shown in Figs. 2 to 5.

Like parts are indicated by similar characters of reference throughout the several views.

The radiator forming the subject matter 60 hereof is of the cellular type presenting a front surface of pleasing appearance divided into a multitude of angular cells of equal proportion.

In constructing the radiator there is employed a main frame having in its upper portion thereof a receiving chamber 1 and in its lower portion a dispensing chamber 2 connected with the receiver chamber by a plurality of conduits through which the water passes from the chamber 1 to the chamber 2. These conduits may be either continuous from one chamber to the other in the manner well known in radiator construction or they may be of short length and arranged in tiers separated by intermediate water spaces or auxiliary chambers common to all the conduits of the tier as shown in Fig. 1.

The conduits are formed by arranging a 80 plurality of similar units side by side but separated one from the other to form intermediate water spaces or passages. The units which are all identical in construction are each formed of a single continuous strip of 85 material folded or bent upon itself at intervals into a series of loops or bights to form a succession of cellular spaces. In the construction shown in Figs. 2 to 7 inclusive there are formed two parallel series of rectangular cells, while the constructions shown in Figs. 8 and 9 disclose single series of triangular cells.

In constructing the unit the strip of material is bent upon itself at intervals 95 throughout a succession of bends or bights to form a series of loop like convolutions thereby producing a meandering design. The meander line upon which the strip is bent varies slightly to produce the different 100 designs shown in Figs. 6 to 9 inclusive.

In the construction shown in Figs. 2 to 6 which embodies two series of cellular spaces, the cells of one series being on a level with those of the other series, a strip of material is carried laterally, as at 7, from one side to the other of the unit, then is bent at right angles to form one side of the unit,

as at 8, and is extended a distance of one space or cell. It is then bent inward or laterally, as at 9, a distance of one space or cell thence longitudinally, as at 10, to form 5 an intermediate septum a distance of one space or cell to the first mentioned lateral portion 7 in parallel relation with which the strip is continued to the opposite side of the unit. It is then bent in a longitudinal direction, as at 11, to form a portion 10 of the opposite side of the unit, being so extended a distance equal to one space or cell and is thence carried laterally, as at 7', to the opposite side of the unit. The same 15 sequence of angular bends is repeated throughout the unit. The particular convolution of the strip formed by its succession of angular bends or meandrine turns is clearly illustrated in Fig. 2 in which the 20 unit is shown in a recumbent position.

Fig. 7 discloses a construction similar to Fig. 6 except that the cellular spaces of one series do not register with those of the other series but are offset in relation thereto. The 25 unit illustrated in Fig. 7 is formed by extending the strip of material laterally, as at 12, a distance equal to one space or cell, or to half the width of the unit, thence longitudinally, as at 13, to form an intermediate 30 septum a distance of one half a cell or space thence laterally, as at 14, a full cell or space to the opposite side of the unit, whereupon the strip is bent longitudinally, at right angles as at 15 to form the side of the unit 35 and is so extended the distance of one space or cell thence is bent inward an equal distance, as at 16, and longitudinally, as at 17, a half space or cell thence laterally, as at 18, a distance equal to one space or cell to 40 the side of the unit from which the strip originally started and is thence extended longitudinally at right angles, as at 19, forming one side of the unit a distance of one cell, whereupon this sequence of angular bends 45 is repeated throughout the length of the unit.

In the construction shown in Fig. 8 there is disclosed but one series of cellular spaces which are triangular in form and in this 50 case are more particularly in the form of a right angled triangle. The unit is formed by extending the strip of material laterally from one side to the other of the unit, as at 20, thence longitudinally, as at 21, to form one side wall thereof a distance of one space 55 from which point the strip is extended diagonally upward and laterally, as at 22 to the starting point at the opposite side of the unit from which point it is extended longitudinally, as at 23, to form the opposite 60 walls of the unit a distance of one space and is projected then laterally, as at 20', to the opposite side of the unit thereby completing one sequence of bends or convolutions which sequence is repeated a number 65 of times to complete the unit. In order that

each cell may rest firmly upon the next cell of the series a flattened surface 4 is provided adjacent to each angle of the cells.

Fig. 9 discloses a construction embodying a single series of triangular cells which 70 differ from the triangular cells of Fig. 8 only in that they are isosceles in form instead of right angled. In constructing the unit shown in Fig. 9 the strip of material is extended diagonally across the unit from 75 one side to the other thereof, as at 24, thence longitudinally, as at 25 to form one side wall of the unit from which point it is extended diagonally upward, as at 26, to the starting point to complete the first cell and is carried thence longitudinally, as at 27, to form the opposite side wall of the unit and extends thence diagonally upward and laterally, as at 24', to the opposite side of the 80 unit thereby completing the sequence of 85 bends which may be continued indefinitely.

The radiator unit formed by any one of the constructions before described is further provided with lateral projecting shoulders 5 adjacent to each edge thereof. The lateral shoulders 5 provide flat bearing surfaces which contact with the corresponding flat surfaces of the succeeding unit when the units are arranged side by side as shown in Fig. 4. These lateral shoulders 5 serve 90 to space the units one from the other thereby providing intermediate water spaces or passages 3 of which said shoulders 5 form the end walls. In addition to being provided with the lateral shoulders or ledges 5 the 95 side walls of the units are preferably though not necessarily provided with grooved depressions 6 which as shown in Figs. 2 to 5 inclusive are located in the outward lateral wall of each of the cellular spaces and intermediate the lateral projecting shoulders or ledges 5. These grooved depressions or beads formed in the side walls of the radiator unit serve to strengthen and stiffen the 100 unit and furthermore provide a series of enlargements within the water spaces or conduits as is clearly shown in Fig. 5 thereby giving to the water a more or less tortuous 105 passage from one chamber to the other. The radiator units as herein described may 110 be formed in continuous sections of great length to be divided subsequently into shorter lengths according to the dimensions 115 of the radiator to be constructed. Inasmuch as the radiator unit is formed throughout of 120 but a single strip of material the possibility of leakage is reduced to minimum. As each radiator unit comprises but a single strip and all of the radiator units employed are 125 identical the cost of construction is reduced to minimum. After the several radiator units have been arranged side by side as shown in Fig. 4 they are dipped into molten solder or are otherwise united one to the other by any suitable method whereby the 130

plurality of radiator units will be formed into an integral body, or core. It is to be noted that the construction described provides a broad flat surface at opposite terminals of the unit to facilitate the connection of the core or body with the chambers.

From the above description it will be apparent that there is thus produced a device of the character described possessing the particular features of advantage before enumerated as desirable but which obviously is susceptible of modification in its form, proportion, detail construction and arrangement of parts without departing from the principle involved or sacrificing any of its advantages.

While in order to comply with the statute, the invention has been herein described in language more or less specific as to certain structural features, it is to be understood that the invention is not limited to any specific details but that the means and mechanism herein shown and described comprise but one mode of putting the invention into effect and the invention is therefor claimed broadly in any of its possible forms or modifications within the scope of the appended claims.

Having thus described my invention, I claim;

1. A radiator including a plurality of spaced conduits the side walls of succeeding conduits comprising a strip of material bent upon itself to form a succession of oppositely disposed loops, each loop having a flat side, the flat sides of alternate loops being alined one with the other to form side walls of succeeding conduits.

2. A radiator including a plurality of spaced conduits formed by a series of radiator units arranged side by side and connected one to the other in spaced relation, each of said units comprising a strip of material bent upon itself throughout a meandrous formation to form a succession of loops each successive loop being oppositely disposed and having an exterior face alined with the exterior face of the second preceeding loop to form two separated parallel walls.

3. A radiator including a plurality of spaced conduits formed by a series of radiator units arranged side by side and connected one to the other in spaced relation, each of said units comprising two parallel side walls constituting side walls of succeeding conduits spaced one from the other and connected at intervals by transverse partitions dividing the intermediate space into a

series of cellular spaces, formed from a strip of material bent upon itself throughout a meandrous formation to form in succession a portion of the side wall of one conduit, a transverse partition extending to the succeeding conduit a portion of the side wall of

the succeeding conduit, and a transverse partition returning to the first mentioned conduit such succession of side portions and transverse partitions being repeated throughout the conduits.

4. A radiator including a plurality of spaced conduits formed by a series of radiator units arranged side by side and connected one to the other in spaced relation, each of said units comprising a continuous piece of material bent upon itself throughout a meandrous formation, the material being first extended to form a portion of one side of one conduit, thence transversely to the adjacent side of the succeeding conduit, thence in a direction parallel with the first mentioned portion to form a portion of the parallel side of the adjacent conduit, thence returning to the first mentioned conduit and extending in a plane common with the first mentioned section, such meandrous convolutions being continued throughout the length of the conduits.

5. A radiator including a plurality of spaced conduits formed by a series of radiator units arranged side by side and connected one to the other in spaced relation, each of said units comprising a continuous piece of material bent upon itself throughout a meandrous formation, said piece of material being extended longitudinally to form a portion of one side of the unit, thence transversely a distance equal to half the thickness of the unit, thence in a longitudinal direction, substantially parallel to the first mentioned section to form a portion of an intermediate septum, thence transversely to the opposite side of the unit where the material is extended longitudinally parallel to the formerly mentioned longitudinal sections, the material being extended thence transversely to the initial side, such successions of angular bends being successively repeated throughout the length of the unit.

6. A radiator including a plurality of spaced conduits formed by a series of radiator units arranged side by side and connected one to the other in spaced relation, each of said units comprising a continuous piece of material bent upon itself throughout a meandrous formation to form a succession of substantially reversed S shaped convolutions, the final terminus of one S shaped convolution being extended to the initial terminus of the succeeding S shaped convolution, the successive convolutions being in contact one with the other thereby forming two continuous parallel surfaces spaced one from the other.

7. A radiator including a plurality of spaced conduits the adjacent walls of succeeding conduits comprising a single continuous strip of material bent upon itself throughout a series of oppositely disposed bights, with each bight contacting the ad-

adjacent bights the sides of succeeding bights forming portions of the side walls for separate conduits.

8. A radiator including a plurality of spaced conduits formed by a series of radiator units arranged side by side and connected one to the other in spaced relation, each of said units comprising a single continuous strip of material bent throughout a meanderous formation to form a series of oppositely disposed bights, each bight contacting the adjacent bights and having formed in its exterior face a grooved depression of less length than the width of the strip whereby an ungrooved portion of the strip will remain beyond the opposite terminals of said groove.

9. In a radiator embodying a plurality of

spaced conduits, a plurality of radiator units each of which consists of the adjacent side walls of succeeding conduits connected one to the other but spaced apart and comprises a strip of material bent into a succession of loops having flat sides alined one with the other, the flat sides of the loops being indented, the indentations of the adjacent loops registering one with the other to form a continuous channel.

In testimony whereof, I have hereunto set my hand this 25th day of March 1912 20
A. D.

KINDERMAN M. BOBLETT.
